UNITED STATES PATENT OFFICE

JOHN C. MILLER, OF CANTONMENT, FLORIDA

MOLD

Application filed December 31, 1928. Serial No. 329,633.

My invention relates to improvements in molds and particularly to such as are adapted for use in the manufacture of pottery in general and flower pots in particular, it being understood, of course, that the invention is capable of other uses.

Briefly stated the invention has for an important object the provision of a novel and improved mold which comprises a minimum number of very simple and easily assembled parts, the nature of which eliminate the necessity for clamps and fastenings.

Another object of the invention is to provide a device of this kind which will be highly efficient in practical use and which will enable high class work to be turned out with great rapidity,—there being provided mounting means whereby the mold will be rotatably supported so as to facilitate tamping of plastic material therein.

Another object of the invention resides in the provision of a novel support for the work whereby the completed pot or work can be stripped off of the core without injury or the exercise of unusual skill.

The invention further contemplates novel means for producing surface ornamentation at the mouth of the work and means for holding the aforementioned means in operative position and proper assembly with the other elements of the mold during the molding operation.

The invention also resides in certain novel features of construction, combination and arrangement of the various parts,—and in modes of operation to be hereinafter described and claimed.

For a better understanding of the invention reference should be had to the accompanying drawings in connection with the following descriptive matter,—the drawings illustrate what now appears to be a preferred embodiment of the invention. However, it is to be understood that the invention is capable of other mechanical expressions within the spirit and scope of the subject matter claimed hereinafter.

In the drawings, wherein the same reference characters have been used to designate the same parts in all views,—

Figure 1 is a perspective view showing the mold assembled with a completed flower pot therein;

Figure 2 is a fragmentary cross-sectional view taken on the line 2—2 of Figure 1;

Figure 3 is a group perspective view of certain parts of the mold;

Figure 4 is a perspective view of a completed flower pot made in the mold.

Figure 5 is a vertical sectional view of a modification;

Figure 6 is a top plan view thereof, and

Figure 7 is a group perspective view of certain parts of such modification.

Referring specifically to the drawings, numeral 5 denoted a base which is provided with a central upstanding boss 5^a. Suitably secured in the boss 5^a and extending above the same is a hard steel rod 6, which serves as a pivot for the hub 8^a of a spider 8,—the hub 8^a of said spider being supported upon the boss 5^a of the base, as shown in Figures 1 and 2.

The spider is of the three-armed variety and has the ends of its arms bent laterally upward, as indicated at 8^b.

The novel mold comprehends a crown-like core 9, which is preferably of hollow construction with its upper or closed end rounded in semi-spherical fashion as at 9^b and provided with a medial hole 9^a for the reception of the pivot rod 6, previously referred to. The core 9 is supported upon fixed cleats 10 disposed upon the upper faces of the arms of the spider 8, as best shown in Figures 2 and 3, said cleats having studs 10^a arranged to be disposed within the core 9 to prevent shifting of the same off the cleats. The advantage cleats 10 for spacing the core 9 from the spider 8 is to assure the even setting of the core, uninfluenced or disturbed by any accumulation of clay or plastic material that may perchance be disposed upon the upper surface of the spider arms.

Supported in part by the outwardly tapered surface of the core 9 and in part by the upstanding ends 8^b of the spider arms is the ring 11. It is to be noted that the inner edge of the ring is beveled to conform to the outward bevel of the core 9.

Having applied the ring 11, as aforesaid, the semi-circular bead defining ring segments 12 are disposed upon the ring 11 with their ends in contact. The outer casing or shell 14 is now lowered into place. It will be noted that the shell or casing 9 has the general outline or contour of the core 9, except that adjacent its diametrically wider end it is provided with an off-set 14^a to receive 5 the ring segments 12. Figure 3 indicates that each ring segment 12 is provided with radially extending lugs 13. The purpose of these lugs 13 is to assure engagement of the end of said semi-circular segments or sections 10 12. This is secured by the clamping action of the enlarged mouth or end portion 14^a of 15 the shell 14. This portion engages the lugs 13 and forces the ends of the ring sections 12 into engagement. Of course there may be 20 any number of ring segments 12 to make up the completed die or ring.

It is evident from the showing in Figures 1 and 2 that the upturned ends 8^b of the spider arms serve to guide and confine the 25 shell 14 in place and thereby hold the entire mold assembly against relative lateral displacement.

It is important to note at this time that 30 since the shell supporting ring 11 engages lateral spider arm ends 8^b and core 9, it serves to hold the core in place against lateral shifting on the lugs 10. This is a very 35 advantageous feature of the mold assembly and enables me to eliminate the cleat studs 10^a if I wish to do so,—although I prefer to retain the cleat studs 10^a for the purpose of holding the core in place pending application of ring 11.

Having assembled the mold, as aforesaid, 40 the plastic or other material is tamped or poured into the space between the shell 14 and the core 9. The mounting of the spider upon the base boss 5^a and about the standard or pin 6 enables the entire spider and mold 45 to be rotated so that more efficient tamping can be had and a better job generally produced. Of course, the standard 6 serves the function of providing the hole 15^a in the bottom of the completed flower pot 15. 50 Having completed the formation of the pot 15 by the tamping process in an obvious way the completed job is ready for removal from the mold.

Removal of the pot 15 from the mold is effected by first removing the shell 14. The ring segments 12 can be left in place. The ring 11 is now grasped and lifted up, thus stripping the pot 15 from the core 9. The ring segment 12 can now be removed.

It is desired to state that the core 9 will necessarily be of very heavy material so that it will maintain its seated position upon the spider while the pot is being lifted off through the instrumentality of the ring 11.

It is believed from the foregoing descrip-

tion, taken in connection with the accompanying drawings, that the novel features and advantages of the invention will be readily apparent to those skilled in the art. The rib 12^a of ring segments 12 produce the bead or groove 15^a in the pot, as shown, and many other designs may be had by placing other rings of different figures or designs as these can be made in segments of 4 and 6 to allow their removal.

In Figure 5 a modified form of the invention is shown illustrating its application to the manufacture of square vessels or vessels which will be of such form that the outer shell cannot be slid off of the completed vessel. Here the stand or base 20 has the central boss 21 carrying the upstanding hard metal rod 22 corresponding to elements 5, 5^a, 6 in Figure 2. 23 designates the hub of the spider having the arms 24 of which there are four instead of three, as in Figure 3. The plane surfaced core member 27 rests upon cleats 26 carried by the arms 24 and rising from the cleats are studs 28 adapted to be disposed adjacent the inner surfaces of the wall of the core 27 to prevent any substantial lateral shifting of the core on the cleats. In this form of the invention instead of the ring 11 of Figure 3, I employ the frame-like pallet 29 which is supported by the outwardly flanged walls of the core 27 and the upturned outer ends 24^a of the spider arms 24. The pallet or frame member 29 supports the sectional shell member which comprises in the illustrated instance four sections 31, which are compoundly and otherwise curved in the direction of their length, (or has dies), thus making it impossible to slide the composite shell, made up of said sections, off of the completed pot upon the core 27. Intermediate the ends and at each side thereof each of the sections 31 has an outwardly protruding lug 32. The sections 31 are assembled upon the spider or rather upon the pallet or frame-member 29. One of the upturned spider arms 24^a will engage the outer surface of each of the sections 31 intermediate the side edges thereof. This will cause the beveled side edges of adjacent sections 31 to lie in flat contact. In order to clamp the assembled sections 31 together, I employ a ring or annulus 33 which may comprise hinged sections, but which in the present instance is shown integral. The ring 33 has inwardly projecting confining lugs 34 which are adapted to seat outwardly of the pair of lugs of adjacent sections 31 at each corner of the shell formed by said sections. Since in the present instance the composite shell 31, 31, etc., is shown with a decided flare outwardly of its upper portion, as shown in position on the mold, the ring 33 can be forced downwardly to clamp the section lugs 32 so as to rigidly hold the assembled shell in assembled condition while the plastic material is dis-

posed between the shell and the core to define the vessels 36. Manifestly, the inner surface of the sections 31 comprising the outer shell may be ornamented in any preferred manner so as to give the exterior of the pot 35 any predetermined ornamental beading or figuring.

On completing of the molding operation the ring 33 is removed and the sections 31 taken out whereupon the completed pot can be stripped from the core 27 to elevation of the frame or pallet 30, as will be evident.

Having thus described my invention, what I claim as new and desire to secure by Letters Patent is:

1. The combination of a mold comprising a base, a support rotatably journaled upon said base, a core carried by said support, said support having extensions extending beyond 20 said core on two sides thereof, said extensions having lateral confining flanges, a work supporting member removably carried by said core and surrounding the same, dies adapted to be supported by said work supporting 25 member for effecting an ornamentation of the work, and a shell adapted to be disposed about said core and supported by said work supporting member, the shell and core being spaced to receive the plastic molding material, 30 and the lateral ends of said extensions engaging said shell to maintain the same concentric with said core.

2. A mold comprising a support, a core removably mounted on said support, a shell 35 adapted to be disposed about said core, means for closing the space between said core and shell at the end adjacent said support, said means providing a support for said shell, die means removably supported upon said space closing 40 means, and said die means being confined by said shell.

3. The combination set forth in claim 2,— and said space closing and shell supporting means being removable to strip the completed 45 molded article from said core.

4. The combination set forth in claim 2,— said space closing and shell supporting means being movable relatively of said core to strip the molded article therefrom, and said base 50 having means cooperating with said core for confining said means and shell in a predetermined relative position with respect to said core.

5. The combination set forth in claim 2,— 55 and including dies carried by said aforementioned means, and said shell having means for holding said dies in place.

6. In a device of the class described, a support, a core positionable upon said support, 60 upstanding portions extending from said support outwardly of said core and spaced therefrom, a shell, supporting means for said shell and carried by said support, and said supporting means engaging the upstanding 65 portions of said first-named support and the

sides of said core whereby to hold the same against lateral shifting on said support.

7. In a device of the class described comprising a base, a core freely supported upon said base, a shell of greater cross section than said core and positionable above the same, means positionable at one end of said core and adapted to engage the shell to maintain the same space equidistance at all points from the core, and said base having means engaging the outer surface of said shells to prevent shifting of the assembly relative of the base.

8. A mold comprising a support, a core removably mounted on said support, a shell adapted to be disposed about said core, means for closing the space between said core and shell at the end adjacent said base, said means providing a support for said shell, die means removably supported upon said space closing means.

In testimony whereof I affix my signature.

JOHN C. MILLER.
